UNITED STATES PATENT OFFICE.

ALEXANDER MAGEE, OF ST. LOUIS, MISSOURI, ASSIGNOR TO THE ST. LOUIS CAR WHEEL COMPANY, OF SAME PLACE.

MACHINE FOR GRINDING CAR-WHEELS.

SPECIFICATION forming part of Letters Patent No. 601,269, dated March 29, 1898.

Application filed July 8, 1897. Serial No. 643,808. (No model.)

To all whom it may concern:

Be it known that I, ALEXANDER MAGEE, a citizen of the United States, residing at the city of St. Louis, in the State of Missouri, have 5 invented a certain new and useful Machine for Grinding Car-Wheels, of which the following is such a full, clear, and exact description as will enable any one skilled in the art to which it appertains to make and use the same, 10 reference being had to the accompanying drawings, forming part of this specification.

The object of my invention is to provide a machine for grinding car-wheels in which the emery-wheel is carried by a swinging frame 15 in such a way that the shaft of the emery-wheel can be inclined at will, so that the emery-wheel will make proper contact with the face of the car-wheel and so that the emery-wheel can be moved laterally across 20 the face of the car-wheel.

My invention consists in the various novel features and details of construction described in the following specification and pointed out in the claims affixed hereto.

25 In the accompanying drawings, which illustrate a machine made in accordance with my invention, Figure 1 is a front elevation. Fig. 2 is a view showing a detail of construction. Fig. 3 is a side elevation, and Fig. 4 is a 30 view showing a detail of construction.

Like marks of reference refer to similar parts in the several views of the drawings.

5 is the bed-plate, on which are formed seats 6, in which are rigidly secured two bars 7. 35 Carried by the bars 7 is a sliding plate 8, which supports the working parts of the machine. Pivoted to a lug 9 on the bed-plate 5 is a lever 10. Pivoted to the lever 10 is one 40 end of a link 11, the other end of which is pivoted to the sliding plate 8. Carried by the sliding plate 8 are two brackets 12, in which is pivoted a yoke 13. In the yoke 13 is journaled a shaft 14, on which is a pulley 15, around which the driving-belt passes, and a 45 pulley 16. Rigidly carried by the yoke 13 and preferably formed integral therewith is a cylindrical portion 17, which is bored out for the reception of a stem 18. The stem 18 is free to slide in the part 17, but is kept from 50 rotating by a feather 18^a or other suitable means. In the bottom of the part 17 is a

screw 19, by means of which the stem 18 can be forced outward. On the stem 18 is rigidly secured a collar 20. On the collar 20 is carried a projection or lug 21, in which is pivoted 55 one end of an extensible connecting-rod 22. The rod 22 is composed of two end pieces provided with right and left hand threads and a turnbuckle 23. The other end of the rod 22 is pivoted to an arm 24, carried by a rock- 60 shaft 25, journaled in brackets carried on the sliding plate 8. The motion of the shaft 25 is controlled by a lever 26, which is rigidly secured to the end of the same.

28 is a hollow cylindrical member carried 65 by a yoke 29 and oscillating on the end of the stem 18. In the yoke 29 is journaled a shaft 30, on which is carried a pulley 31 and an emery-wheel 32. On the collar 20 is an arm 33, to which is pivotally secured a block 34, 70 in which is journaled a rod 35, provided with a hand-wheel 36. On the yoke 29 is an arm 37, to which is pivotally secured an internally-threaded block 38, which receives the threaded end of the rod 35. To the yoke 29 75 is secured a rope 39, to which may be secured a weight to counterbalance the weight of the emery-wheel 32 and parts carrying it.

40 is the car-wheel to be ground and which may be supported in any suitable manner. 80

The belts have been omitted in the drawings to better illustrate the machine, as the operation can be readily understood without them.

The operation of my machine is as follows: 85 The driving-belt is passed around the pulley 15 and the pulleys 16 and 31 are connected by a belt, so that the frame carrying the emery-wheel 32 may be swung without stopping the rotation of said emery-wheel. The rais- 90 ing and lowering of the emery-wheel is controlled by the lever 26. When the lever 26 is moved toward the front of the machine, the shaft 25 is rotated and the motion com- 95 municated through the arm 24 and connect- 95 ing-rod 22 to the frame carrying the emery- wheel, thus raising it from the car-wheel 40. When it is desired to remove a car-wheel and place a new one in position, the lever 26 is moved to its extreme forward position and 100 allowed to rest upon one of the brackets 12. The lever will remain in this position, as the

arm 24 and rod 22 will have passed the point where they were in a straight line and the weight of the parts will therefore tend to move the lever farther in the same direction. By 5 rotating the turnbuckle 23 the length of the rod 22 can be adjusted to adapt the machine to different sizes of car-wheels. In order to secure proper contact between the emery-wheel and the car-wheel, the hand-wheel 36 10 is rotated, thus turning the yoke 29 around the stem 18 and inclining the shaft of the emery-wheel. The movement of the emery-wheel across the face of the car-wheel is controlled by the lever 10, by means of which the 15 sliding plate 8, carrying the working parts, is moved on the rods 7. To tighten or loosen the belt connecting the pulleys 16 and 31, the screw 19 is turned in one direction or the other.

I am aware that grinding-machines with 20 swinging frames and also with rotating frames have been used heretofore and do not wish to be understood as broadly claiming the same.

Having fully described my invention, what I claim as new, and desire to secure by Letters 25 Patent of the United States, is—

1. In a grinding-machine, a suitable base, a sliding member carried thereby, means for actuating said sliding member, a swinging frame carried by said sliding member, means 30 for actuating said swinging frame, a pivotally-mounted frame carried by said swinging frame, a grinding-wheel carried by said pivotally-mounted frame, and mechanism for turning said pivotally-mounted frame to incline the axis of said grinding-wheel.

2. In a grinding-machine, a suitable base, a sliding member carried thereby, means for actuating said sliding member, a swinging frame carried by said sliding member, adjustable means for actuating said swinging frame, a pivotally-mounted frame carried by said swinging frame, a grinding-wheel carried by said pivotally-mounted frame, and mechanism for turning said pivotally-mounted frame 45 to incline the axis of said grinding-wheel.

3. In a wheel-grinding machine, a suitable base, a yoke pivotally mounted thereon, a non-rotary stem carried by said yoke, means for moving said stem longitudinally, a second yoke pivotally mounted on said stem, means 50 for turning said latter-named yoke, and a grinding-wheel carried by said latter-named yoke.

4. In a wheel-grinding machine, a suitable base, a sliding member carried thereby, a yoke 55 pivotally mounted on said sliding member, a non-rotary stem carried by said yoke, means for moving said stem longitudinally, a second yoke pivotally mounted on said stem, means for turning said latter-named yoke, 60 and a grinding-wheel carried by said latter-named yoke.

5. In a wheel-grinding machine, a suitable base, a yoke pivotally mounted thereon, a non-rotary stem carried by said yoke, means 65 for moving said stem longitudinally, a second yoke pivotally mounted on said stem, a grinding-wheel carried by said second yoke, an arm rigidly carried by said stem, and means interposed between said arm and said 70 second yoke for moving said second yoke to incline the axis of said grinding-wheel.

6. In a wheel-grinding machine, a suitable base, a sliding member carried thereby, a yoke pivotally mounted on said sliding member, a non-rotary stem carried by said yoke, means for moving said stem longitudinally, a second yoke pivotally mounted on said stem, a grinding-wheel carried by said second yoke, an arm rigidly carried by said stem, 75 and means interposed between said arm and said second yoke for moving said second yoke to incline the axis of said grinding-wheel.

In testimony whereof I have hereunto set my hand and affixed my seal in the presence 85 of the two subscribing witnesses.

ALEXANDER MAGEE. [L. S.]
